UNITED STATES PATENT OFFICE.

HENRY GEISENHÖNER, OF SCHENECTADY, NEW YORK, ASSIGNOR TO
GENERAL ELECTRIC COMPANY, A CORPORATION OF NEW YORK.

SNAP-SWITCH.

No. 819,645.

Specification of Letters Patent.

Patented May 1, 1906.

Application filed May 10, 1902. Serial No. 106,751.

To all whom it may concern:

Be it known that I, HENRY GEISENHÖNER, a citizen of the United States, residing at Schenectady, county of Schenectady, State 5 of New York, have invented certain new and useful Improvements in Snap-Switches, of which the following is a specification.

My invention relates to snap-switches for electrical purposes, and has for its object to 10 provide such a switch with actuating means consisting of few parts which will operate to positively release and arrest the switch-blades and also effectually withstand the hammering effect to which it is subjected by 15 the sudden starting and stopping of the movable parts.

My invention will be more readily understood by reference to the accompanying drawings, forming a part of this specification, 20 in which—

Figure 1 is a vertical section of a snap-switch embodying one form of my invention. Fig. 2 is an enlarged bottom plan view of the retainer, the locking-pawl, and the controlling-cam in locked position; and Fig. 3 is a 25 similar view with the parts shown in the position assumed at the instant of release.

My invention is shown in the drawings applied to a double or two-blade switch having 30 a circular base 2, of wood or other suitable material, and upon the upper surface of which are secured binding parts 3, provided with contact-clips 4, two of which are in one plane and two in another, according to the usual arrangement in this type of devices, so as to 35 register, respectively, with the switch-blades 5 and 6, carried in different planes upon their support 7. The circular base 2 is provided with a central aperture, in the upper part of 40 which the reduced lower end of the blade-support 7 is journaled. Just below the end of blade-support 7 the walls of the central aperture are rabbeted for the reception of the circular bearing-plate 9, which is held loosely 45 in place by the retainer-ring 10, which underlies the outer periphery of the bearing-plate 9 in and is seated in a second rabbeted recess in the wall of the central aperture and held therein by screws 11, extending down from the upper 50 side of the base 2 and engaging tapped holes in the said retainer-ring 10. The blade-support 7 is fastened to the bearing-plate 9 by suitable means, as screws extending through the one into the other. The actuating-spin-

dle 12, which is provided with a thumb-piece 55 13 at its upper end and a contracted journal 14 and shoulder 15 at its lower end, is axially journaled in the blade-support 7 and bearing-plate 9 and is yieldingly connected thereto by means of the coiled spring 16, surrounding 60 the spindle and having one of its ends entering a hole in the side of the spindle, the other end engaging a pin 17 on the upper surface of the bearing-plate 9. The blade-support 7 is provided with a small chamber to accommodate the spring 16.

The lower end of the actuating-spindle 12 bears at its shoulder 15 upon the upper surface of the bearing-plate 9, and beneath said plate it is secured to the controlling-cam 18 70 by upsetting or other suitable means. Eccentrically pivoted at 19 upon the lower face of the bearing-plate 9 is the locking-pawl 20, adapted to engage the inwardly-projecting shoulders 21 of the retaining-ring 10 and lock 75 the bearing-plate 9 and the parts connected therewith against rotation while the actuating-spindle 12 is being rotated to put the spring 16 under tension.

As indicated in Figs. 2 and 3, the bearing-surfaces of shoulders 21 slope in the direction of the pivot-point 19 of the pawl 20, so that the latter normally tends to slide inward and off from the former. The cam 18 is shaped and proportioned so that it bears upon the 80 inner edge of the shouldered end of the pawl 20 and holds it pressed outward against the tendency of the pawl to move inward, due to the inclined bearing-surfaces. The cam radius is abruptly shortened at a point 22, 85 which when brought opposite the inner bearing edge of the pawl permits it to move inwardly sufficient to escape the shoulder 21, as indicated in Fig. 3. The cam 18 when at rest occupies substantially the position indicated in Fig. 2, and accordingly as the actuating-spindle 12 is turned to bring the cam into the position of Fig. 3 the coiled spring 16 is put under tension, so that the instant the pawl escapes the shoulder of the retaining-ring 10 the blade-support and connected parts are thrown around through an angle of ninety degrees by the recoil of the spring and the pawl 20 engages the next shoulder 21, being forced outward by the action of the cam 18, 90 which, being connected to the actuating-spindle 12, has stood substantially stationary during the movement of the other parts.

In order to insure the inward movement of the pawl 20, if for any reason it should fail to slide readily when the cam 18 has been moved into the position indicated in Fig. 3, I 5 extend the shank of the pawl 20 beyond its pivot-point and so shape its inner edge that it will be engaged by the longer radius of the cam 18, and thereby be positively tilted and released.

10 It is to be noted that at the end of the throw of ninety degrees of the switch-blade support and connected parts the impact due to the unspent forces is received by the full length of the shoulder 21 and coöperating 15 face of the pawl 20, so that the hammer effect is distributed.

What I claim as new, and desire to secure by Letters Patent of the United States, is—

1. In an electric switch, the combination 20 of a stationary retainer, a rotary blade-support, a locking-pawl carried eccentrically by said support, and an actuating-spindle yieldingly connected to said support and provided with means for normally forcing said locking- 25 pawl outward during its travel between stops and its engagement with said retainer.

2. In an electric switch, the combination 30 of a stationary retainer, a rotary blade-support, a locking-pawl pivoted eccentrically upon said support, and an actuating-spindle yieldingly connected to said support and provided with a controlling-cam which operates normally to force said pawl outwardly during its travel between stops and its engagement 35 with said retainer.

3. In an electric switch, the combination of a stationary retainer, a rotary blade-sup-

port, a locking-pawl pivoted eccentrically upon said support and having its shank extended beyond its pivot, and an actuating-spindle yieldingly connected to said support and provided with a cam adapted to bear against said pawl upon either side of its pivot and which operates normally to force said pawl outwardly during its travel from 45 stop to stop and its engagement with said retainer.

4. In an electric switch, the combination of a stationary retainer having inclined shoulders, a rotary blade-support, a locking-pawl carried by said support and having an inclined shoulder formed at an oblique angle to the radius of the pawl at that point, and an actuating-spindle having spring connection with said support and provided with means for 50 normally restraining the sliding tendency of the said pawl with reference to the inclined shoulders of the stationary retainer.

5. The combination of the base 2, the blade-support 7 mounted to rotate upon the 60 upper side of said base, the stationary retainer 10 mounted upon the under side of said base, the actuating-spindle 12 extending axially through said support and connected thereto by the spirng 16, a locking-pawl 65 20 adapted to engage said retainer, and a cam carried by said spindle and normally operating to force said pawl radially outward.

In witness whereof I have hereunto set my hand this 8th day of May, 1902.

HENRY GEISENHÖNER.
